US00D806246S

(12) **United States Design Patent** (10) Patent No.: **US D806,246 S**
(45) Date of Patent: **** Dec. 26, 2017**

(54) LANCET COVER	4,157,086 A	6/1979	Maiorano et al.
(71) Applicant: Steven Schraga , Surfside, FL (US)	4,203,446 A	5/1980	Hofert et al.
	4,219,055 A	8/1980	Wright
	4,252,159 A	2/1981	Maki
(72) Inventor: Steven Schraga , Surfside, FL (US)	4,257,561 A	3/1981	McKinney
	4,274,453 A	6/1981	Lee
	4,338,871 A	7/1982	van der Lely
(**) Term: 15 Years	4,357,971 A	11/1982	Friedman
	4,373,526 A	2/1983	Kling
(21) Appl. No.: 29/555,896	4,388,925 A	6/1983	Burns
	4,414,975 A	11/1983	Ryder et al.
(22) Filed: Feb. 25, 2016	4,426,105 A	1/1984	Plaquin et al.
(51) LOC (10) Cl. 24-02	4,434,820 A	3/1984	Glass
(52) U.S. Cl.	4,438,770 A	3/1984	Unger et al.
USPC D24/146	4,445,896 A	5/1984	Gianturco
(58) Field of Classification Search	4,449,529 A	5/1984	Burns et al.
USPC D24/146, 147, 127, 130, 133; 606/167,	4,469,110 A	9/1984	Slama
606/181, 182, 184; 30/342; D30/131,	4,475,915 A	10/1984	Sloane
D30/133, 130, 155, 199; D1/101, 107,	4,489,766 A	12/1984	Montada
D1/129, 199	4,517,978 A	5/1985	Levin et al.
CPC A61B 5/150022; A61B 5/1411; A61B	4,527,561 A	7/1985	Burns
5/150412; A61B 5/150519	4,535,769 A	8/1985	Burns
See application file for complete search history.	4,539,988 A	9/1985	Shirley et al.
	4,553,541 A	11/1985	Burns
(56) References Cited	4,573,976 A	3/1986	Sampson et al.
U.S. PATENT DOCUMENTS	4,610,620 A	9/1986	Gray

CLAIM

The ornamental design for a lancet cover, as shown and described.

DESCRIPTION

FIG. 1 is a front perspective view illustrating my design for a lancet cover;

FIG. 2 is a front view thereof;

FIG. 3 is a left view thereof;

FIG. 4 is a top view thereof;

FIG. 5 is a right view thereof;

FIG. 6 is a bottom view thereof; and,

FIG. 7 is a rear view thereof.

The broken lines shown in FIGS. 1-7 illustrate environment and form no part of the claimed design.
